H. DEITZ.

CLOSURE.

APPLICATION FILED FEB. 11, 1908.

950,372.

Patented Feb. 22, 1910.

UNITED STATES PATENT OFFICE.

HENRY DEITZ, OF DENVER, COLORADO.

CLOSURE.

950,372.

Specification of Letters Patent. Patented Feb. 22, 1910.

Application filed February 11, 1908. Serial No. 415,293.

To all whom it may concern:

Be it known that I, HENRY DEITZ, a citizen of the United States, residing at the city and county of Denver and State of Colorado, 5 have invented certain new and useful Improvements in Closures; and I do declare the following to be a full, clear, and exact description of the invention, such as will enable others skilled in the art to which it 10 appertains to make and use the same, reference being had to the accompanying drawings, and to the figures of reference marked thereon, which form a part of this specification.

15 My invention relates to improvements in closures for cans or other vessels or receptacles which are usually kept closed except when pouring liquid therefrom.

My improved closure includes a vent 20 which is opened when the closure is adjusted to pour liquid from the can. This closure is of the class which is permitted a partial rotation. When turned in one direction, both the vent opening as well as the 25 opening for the discharge of liquid is closed while when the device is turned in the other direction both of these orifices are open. For convenience of adjustment the stationary part of the closure is provided with two 30 stops adapted to limit the travel of the movable member in both directions. When the travel of the movable part is stopped in one direction, the closure is open for liquid-pouring purposes, while when it reaches its 35 limit of travel in the other direction the device is closed. Between the movable part of the closure and the top of the can, is interposed a quantity of packing material which is held in place by a collar whose upper 40 and lower edges are respectively provided with interiorly and exteriorly projecting flanges, the upper flange serving to maintain the movable part of the closure in place, the latter having an exteriorly 45 projecting flange located beneath the interiorly projecting flange of the collar.

Having briefly outlined my improved construction, I will proceed to describe the same in detail reference being made to the 50 accompanying drawing in which is illustrated an embodiment thereof.

In this drawing, Figure 1 is a section taken through my improved closure also cutting the top of the can or receptacle to 55 which it is applied, the latter being partly

broken away. Fig. 2 is a top plan view of the construction. Fig. 3 is a section taken on the line 3—3 Fig. 1 looking downwardly or in the direction of the arrow. Fig. 4 is a view similar to Fig. 1, a funnel, however, being inserted for purposes of filling. 60

The same reference characters indicate the same parts in all the views.

Let the numeral 5 designate a can or other vessel with which my improved device may 65 be used. As shown in the drawing the top of the can is cut away as shown at 6 and to the top surrounding this opening is applied a collar 7 having an exteriorly projecting flange 8 and an interiorly projecting similar 70 flange 9. Brazed to the collar is a plate 10 which occupies a position in the plane of the flange 8, the plate being applied interiorly and arranged to close the opening 6 except that an orifice 12 is left for inlet and discharge purposes. The plate 10 is provided with a short upwardly turned flange 13 surrounding the orifice 12. Interposed between the plate 10 and the movable part 14 of the closure, is a quantity of packing material 75 15. The movable part 14 of the closure consists of a casing 16 comprising a horizontal top portion, a depending vertical portion 17 and an outwardly turned flange 18 which occupies a position beneath the inwardly turned flange 9 of the collar and is 80 free to rotate between the packing material and the flange 9. This movable closure part is further provided with a bottom plate 18 which is in direct engagement with the packing 85 material and is provided with a discharge opening 19 and a vent orifice 20. The discharge opening 19 registers with an opening 21 formed in the packing material and also with the opening 12. Directly 90 above the opening 19, is an opening 22 formed in the top of the casing which is normally closed by a cover 23, the latter being readily removable for filling purposes. The casing 16 forms an air chamber 24 100 which is in communication with a spout 25 by an opening 26. This spout projects laterally from the casing and is used as a handle for turning the casing. The casing 16 is further provided with a laterally projecting vent tube 27, the same being open at both ends and in communication with the chamber 24. The stationary part of the closure is provided with an open-ended tube 28 which passes through the plate 10 as well 110

as the packing material, and registers with the vent opening 20. This tube also projects a short distance into the can.

When the movable part of the closure is 5 in the position shown in Figs. 1, 2 and 4 it is in position for purposes of discharge, the openings 12, 21 and 19 being in the registering position whereby the liquid is adapted to flow from the can into the chamber 24 10 and thence through the discharge spout 25. When in this position the vent tube 10 registers with the vent orifice 20, whereby air is allowed to flow freely through the tube 27 into the chamber 24 and thence through the 15 vent orifice and the vent tube 28 into the can, to take the place of the removed liquid.

When it is desired to fill the can, the cap 23 is removed, and the spout of a funnel inserted in the registering openings 22, 19, 21 20 and 12. During the filling operation the air escapes from the can through the vent openings which are in position for the purpose. After the can is filled, the casing should be turned to the closed position or that indicated in Fig. 3 in which the opening 19 is 25 closed by the packing material 15. In this event the position of the discharge opening 21 is indicated by the dotted circle. The flange 8 of the collar 7 is provided with two 30 upwardly projecting pins 30 and 31 which are arranged to limit the travel of the casing in both directions, by coming in contact with the spout 25. When the casing is moved to the closed position, the spout engages the 35 stop 30 while when it is moved to the open position, it engages the stop 31.

The vent tube 28 not only serves as a 40 vent passage through the packing disk but also serves to maintain the said disk in a uniform position since the tube passes through the bottom plate 10 of the device which is relatively stationary, being brazed to the collar 7 as heretofore described. It will be understood that it is exceedingly 45 important that the packing disk should maintain a uniform position, in order that the openings therein may register with the vent opening 20 and the discharge opening 19 in the bottom plate 8 of the casing when 50 the latter is adjusted for discharge or filling purposes.

Attention is called to the fact that the 55 plate 10 below the casing which is brazed to the collar 7 on the inside, makes the closure complete independently of the can or vessel to which it is attached. Hence in order to apply it to any vessel or receptacle it is only necessary to cut out an opening of the size of the plate 10 and then 60 apply the collar and its attachments thereto by soldering or otherwise securing the flange

8 to the top of the receptacle. Another novel feature of the device consists in forming an opening 22 in the top of the casing having it so arranged that it shall register 65 with the discharge openings 19, 21 and 12, when the casing is properly adjusted thus permitting the insertion of a funnel for filling purposes as shown in Fig. 4 and heretofore explained. 70

Having thus described my invention, what I claim is:

1. The combination with a can or other receptacle, of a packing disk applied to the top of the can and provided with 75 distinct discharge and vent openings, a collar surrounding said disk and having an interiorly projecting flange, a casing having an air chamber mounted on the disk and an exteriorly projecting flange located beneath 80 the interior flange of the collar, the said casing being provided with an opening in its top in alignment with the discharge opening of the packing disk for the purpose of filling the can, a discharge spout in communication with the casing chamber and adapted to be turned for purposes of discharge, the collar being provided with stops 85 adapted to engage the spout for limiting the travel of the casing in both directions, the 90 said casing being in communication with the discharge and vent openings of the packing disk substantially as described.

2. A closure for cans or other receptacles comprising a packing disk, a collar inclosing 95 said disk, a casing rotatably connected with the collar and engaging the top of the disk, the casing having an air chamber, the bottom of the casing and the disk being provided with discharge and vent openings 100 adapted to register when the casing is properly adjusted, the said openings communicating with the air chamber, the casing having an opening in its top in alignment with the discharge opening in the disk and bottom of the casing, the collar being provided with a bottom plate which the packing plate 105 engages and which is provided with discharge and vent openings registering with those of the disk and the casing when the 110 latter is properly adjusted, and a vent tube inserted in the vent openings of the plate and packing disk whereby the disk is held against movement, substantially as described. 115

In testimony whereof I affix my signature in presence of two witnesses.

HENRY DEITZ.
